Primary Examiner — Janice Patyk*Assistant Examiner* — Kendra L Hebel(74) *Attorney, Agent, or Firm* — Ware, Fressola, Maguire & Barber LLP(57) **CLAIM**

The ornamental design for a whisk, as shown and described.

DESCRIPTION

FIG. 1 is a lower perspective view of a whisk showing the new design;

FIG. 2 is a front view thereof;

FIG. 3 is a rear view of thereof;

FIG. 4 is a first side view thereof;

FIG. 5 is a second side view thereof;

FIG. 6 is a top view of thereof; and,

FIG. 7 is a bottom view of thereof.

The broken lines shown in the drawings are for the purpose of illustrating portions of the whisk that form no part of the claimed design.

1 Claim, 7 Drawing Sheets(56)
